LUBRICATING APPARATUS

Lutwin C. Rotter, Glendale, and Irving H. Mahne, St. Louis, Mo., assignors to Lincoln Engineering Company, St. Louis, Mo., a corporation of Missouri

Application April 3, 1935, Serial No. 14,462

13 Claims. (Cl. 221—47.3)

This invention relates to lubricating apparatus, and with regard to certain more specific features, to a semi-automatic, portable, hand injector pump.

5 Among the several objects of the invention may be noted the provision of a self-priming, single-stroke plunger type of hand pump; the provision of apparatus of the class described in which certain priming air is admitted with the air for motivating the pump, but in which the priming air pressure is not relieved upon exhausting the pump but which is relieved when the pump is disconnected from its source of air supply; the provision of apparatus of the class described in which priming air is used to effect a differential plunger return action but in which during the pumping stroke the differential return action is neutralized so as to obtain maximum pressure from the motivating air used; the provision of apparatus of this class having improved filling means; and the provision of apparatus which is simple in operation and both simple and compact in construction. Other objects will be in part obvious and in part pointed out herein-after.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

35 Fig. 1 is a longitudinal section embodying the invention, certain valve parts having been eliminated for clarity;

40 Fig. 2 is a cross section taken on line 2—2 of Fig. 1 but showing said valve parts;

Fig. 3 is a cross section taken on line 3—3 of Fig. 2;

Fig. 4 is a fragmentary cross section taken on line 4—4 of Fig. 2; and,

45 Fig. 5 is a fragmentary cross section taken on line 5—5 of Fig. 2.

Similar reference characters indicate corresponding parts throughout the several views of the drawing.

50 Referring now more particularly to Fig. 1, there is shown at numeral 1 a cylinder to which is removably threaded and sealed an outlet head 3, the latter carrying an outlet nozzle extension 5 at the end of which is a manually closable nozzle valve 6. The head 3 has therein an out-

let check valve 7. The head 3 is internally provided with a cylinder 9 adapted to slidably receive a plunger 11. The forward end of the plunger 11 is conic as indicated at numeral 13 and the rearward end of the cylinder 9 is beveled as shown at numeral 15 to more readily effect an assembly of the head 3 with the barrel 1. The head 3 also carries an inlet connection 17 for the infilling of lubricant, said connection being provided with an outwardly seating ball 10 check valve 19 to prevent outward flow of lubricant, once the pump has been filled.

5 The plunger 11 is threaded to a rod 21, a suitable cross passage 23 for a wrench or the like being provided for this purpose. A floating follower piston 25 is provided with suitable sealing means 27 operative both in connection with the wall of the cylinder 1 and with said rod 21. The purpose of the piston 25 is to divide the cylinder 1 (Fig. 1) into two compartments, namely, a forwardly located lubricant compartment (to the left of the piston) and a rearwardly located air compartment (to the right of the piston).

10 There is screw threaded and sealed to the rearward end of cylinder 1 a control head 29 which has a closing diaphragm 31 therein.

15 On the inner side of this diaphragm 31 is threaded a differential cylinder 33 which extends coaxially with, and into the cylinder 1. The rear end of the rod 21 carries a differential piston 35 which operates in the cylinder 33. On the other side of the piston 35 is provided a rigid, hollow extension 37 which passes through the diaphragm 31, being packed therein by means 30 of a packing 39. The extending stem 37 carries a power piston 41 upon the right-hand side of the diaphragm 31, said piston 41 operating in a closed cylinder cap 43 screwed to said head 29.

20 As shown in Figs. 2 and 3, the head 29 is provided with an air inlet fitting 47 adapted to receive an air chuck of an air line under pressure. The fitting 47 screws into a recess 49 in which is a valve 51. The recess and the valve may transmit air about the valve (see Fig. 4), 25 due to square, relieved portions 52. Thus air may pass from the fitting 47 and around the valve 51 when the valve is removed from its seat 53. However, the valve is normally pressed to its seat to close off the air by means of a spring 50 55.

The valve 51 has a stem 57 which passes through a passage 59 and to the stem 61 of a second valve 63. The body of the valve 63 snugly but slidably fits the hole in which it works, so 56

that no passage to atmosphere is provided around the valve. However, a passage 54 to atmosphere is provided in the head 29.

A handle 65 pivoted to the head 29 cooperates with the outer end 67 of the valve 63 so that upon pressing the handle 65, said valve 63 may be seated against its seat 45 and the valve 51 unseated from its seat 53, both against the pressure of spring 55 and the air line pressure.

10 Thus, when the valve 51 is unseated, air may flow in from the fitting 47 into the passage 59. A side passage 71 (Fig. 1) communicates with passage 59 and passes into communication with said differential cylinder 33.

15 Beyond the seat 45 there is also a passage 73 communicating from said passage 59 and to the region beneath piston 41 in the cylinder 43. Passage 79 leads from a point ahead of seat 53 to the cylinder 1 (Fig. 3).

20 Operation of the device is as follows, assuming some lubricant to be in the cylinder 1 ahead of piston 25:

By means of an air chuck, an air hose is placed in connection with the air receiving fitting 47. 25 Priming air immediately flows to the cylinder 1 to force the follower 25 against the lubricant ahead of it. The plunger 11 is back and out of cylinder 9, because of air pressure below the differential piston 35. Hence open cylinder 9 is 30 primed by grease under air pressure. The air, normally pressing upon the valve 51 holds it to its seat 53 to check any flow past the same. Next, the nozzle valve 6 is placed in communication with the opening which it is desired to have receive the lubricant. When the lever 65 is pressed, the exhaust valve 63 is seated, the inlet valve 51 is opened and air is admitted to the passage 59, but not to the passage 73. Hence air under pressure passes through the sideward passage 71 40 (Fig. 1) to the cylinder 33 to impress its force upon the top of differential piston 35 to produce a balanced condition and cancelling the return action of air therebeneath.

Some of the charge of air which enters the 45 cylinder 33 passes through the hollow stem 37, via the port 71 and out into the cylinder 43, where it impresses its force upon the top of power piston 41 to force the plunger 11 into the cylinder 9 to discharge lubricant therefrom. In 50 the meantime air exhausts from beneath the piston 41 via passage 54.

Upon releasing the handle 65, the flow of air to the passage 59 is cut off by valve 51, and thus flow is cut off to the top of the piston 41 in the 55 auxiliary cylinder 43. At the same time the valve 63 is opened so that the air in cylinder 43 above piston 41 may exhaust to cylinder 33 through stem 37 and the air from cylinder 33 exhausts via port 71, passage 59, passage 73 and out of 60 port 54. The entire exhausting operation and hence charging operation into cylinder 9 is due to the return movement of piston 35 under the unbalanced condition of pressure therebeneath. Thus another charge of lubricant is drawn into 65 said cylinder 9.

In view of the fact that pressure of air is maintained behind the follower piston 25 and in the cylinder 1 because of passage 79 leading from a point ahead of the valve 51 in communication 70 with the inlet fitting 47, every time that an air line is attached to the fitting 47, priming air is immediately forced into the cylinder 1 behind the follower 25 and said pressure is released as soon as the air line is removed. Thus no reliance 75 is placed upon holding an isolated charge of air

in the cylinder 1. Thus, each time that a connection is made, the device is primed and made ready for a power stroke.

One mode of filling the device is to connect a lubricant filler line to the inlet 17 and force 5 lubricant through the check valve 19 against piston 25 which is thus automatically forced back. At this time there is no air line connected to the fitting 47 so that the air pressure behind the follower piston 25 is atmospheric and as the following 10 proceeds inwardly, the air is exhausted through port 79 and open fitting 47. A stop 81 automatically limits travel of the follower piston 25 and the charge of lubricant.

Sometimes the user is not equipped with filling 15 apparatus of the class above referred to. In this event he may unscrew the front cap 3 and insert the open end of the cylinder 1 (when empty) into a bucket of lubricant. The other cap 29 may then be, or has been previously unscrewed. 20 It is pulled back, thus causing the rod 21 to be withdrawn so that the plunger 11 contacts with the following piston 25. By this means the following 25 piston 25 is withdrawn to draw in lubricant.

It will be noted that the stop 81 is so arranged 25 that the follower in its rearmost position is not interfered with by the differential cylinder 33 when the latter is reinserted by screwing the head 29 back into position on the cylinder 1. Application of air pressure then immediately effects 30 a suction stroke preparatory to a pumping operation, as above disclosed.

It will be noted that the plunger 11 is withdrawn entirely from pump cylinder 9. Upon reentry, the plunger 11 is properly guided within 35 the limits provided by the conic shape 13 and the bevel 15 by reason of the fact that a bearing and guiding action is effected by the follower 25, the differential piston 35 and the power of 40 piston 41.

Among the advantages of the invention may be noted:

1. The provision of priming air behind the lubricant whenever an air line is attached to the compressor; and the provision for automatic release of priming pressure whenever the air line is disconnected, so that the operator is assured when he takes off the heads for filling that no unforeseen exudation will occur.

2. The pressure of the priming air serves (a) 50 to place the lubricant under pressure and (b) to actuate the differential piston 35 so as to draw out the plunger 11 to effect a positive and complete priming charge in the cylinder 9.

3. The air for actuating the power piston 41 is used during its passage to the rear of said piston to balance the differential piston 35 so that the action of the priming air in effecting a suction stroke is offset, and whereby a maximum 60 effect is obtained from the air on the compressing stroke.

4. The device is unitary, compact, easy and safe to operate and fill. No complicated mechanisms are employed.

In view of the above, it will be seen that the several objects of the invention are achieved and other advantageous results attained.

As many changes could be made in carrying out the above constructions without departing from the scope of the invention, it is intended that all matter contained in the above description, or shown in the accompanying drawing shall be interpreted as illustrative and not in a limiting sense.

We claim:

1. In apparatus of the class described, a main cylinder, a head on the forward end of said cylinder carrying a pumping cylinder, a plunger cooperating with said pumping cylinder, a rearward extension from the plunger passing through said main cylinder, a follower in the main cylinder and surrounding said extension, said main cylinder carrying lubricant ahead of said follower and having an air chamber therebehind, an enclosing head on the rear of said cylinder, a power cylinder associated with said head, a differential cylinder extending from said head and into said main cylinder, said extension passing through said differential cylinder and through said head and into the power cylinder and having a hollow portion effecting communication between the differential cylinder and the power end of the power cylinder, a differential piston on the extension in said differential cylinder and a power piston thereon in said power cylinder, said head having passages for introducing priming air into said chamber and air into and out of said differential cylinder and for exhausting air from beneath the power piston and valve means in said rearward head adapted in one position to effect distribution of air to the differential cylinder and hence also to the power end of the power cylinder and in another position to exhaust the differential cylinder and hence also the power end of the power cylinder.
2. In apparatus of the class described, a main cylinder, pumping means at the front end of said cylinder, an extension from said pumping means passing through said cylinder, a follower surrounding said extension and positioned in said main cylinder, an auxiliary power cylinder associated with said main cylinder, a piston in said power cylinder, said extension from the pumping means reaching to and connecting with said power piston, a differential cylinder communicating inwardly with the main cylinder, a differential piston attached to said extension, and in said differential cylinder, means for introducing priming air behind said follower in said main cylinder and hence against the differential piston to effect a suction stroke of said pumping means, means for introducing air pressure against the opposite side of the differential piston to balance the same and means to introduce air to the power side of the power piston when the differential piston is balanced.
3. In apparatus of the class described, a pumping mechanism, a lubricant supply chamber, a follower in said chamber, an air motor for operating said pumping means, means connecting the pumping means and the air motor, a differential piston associated with said connecting means, a cylinder therefor, and valved means adapted in one position of parts to direct air behind said follower and against one side of said differential piston while effecting exhaust from the other side of the differential piston, and in another position to direct air against the opposite side of the differential piston and to the air motor to energize the latter to operate the pumping mechanism.
4. In apparatus of the class described, a pumping mechanism, a lubricant supply chamber, a follower in said chamber, an air motor for operating said pumping means, means connecting the pumping means and the air motor, a differential piston associated with said connecting means, a cylinder therefor, and valved means adapted in one position to direct air behind said follower and against said differential piston to effect a suction stroke of the pumping means and priming thereof in one position of the valve means, and in another position to direct air to said air motor to effect a pumping stroke of said pumping means and at the same time to substantially balance the pressure on said differential piston.
5. In apparatus of the class described, a pumping mechanism, a lubricant supply chamber, a follower in said chamber, an air motor for operating said pumping means, means connecting the pumping means and the air motor, a differential piston attached to said connecting means, a cylinder for said differential piston communicating with the supply chamber behind the follower, and valve means adapted in an original position to direct air behind said follower and hence against said differential piston whereby is effected a suction stroke of the pumping means and priming thereof in one position of the valve means, said valve means being adapted to be placed in another position to direct air to said air motor to effect a pumping stroke of said pumping means and at the same time against the opposite side of the differential piston to substantially balance said differential piston, said valve means in its original position effecting exhaust of the air motor and differential cylinder, whereby said air under pressure for priming again unbalances said differential piston and detachable means for leading air to the valve means, the device having a passage to pass air under pressure to the follower whenever attached but otherwise to exhaust and relieve the pressure on the follower.
6. In apparatus of the class described, a main cylinder, a forward head thereon comprising a pump cylinder having an outlet, a plunger in said pump cylinder, an extension from said plunger reaching axially through said main cylinder, a follower in said main cylinder coaxial with the extension, said plunger being adapted to be drawn back in said pump cylinder, a head enclosing the rear of said main cylinder, a power cylinder extending coaxially rearwardly from said head, a differential cylinder extending coaxially from said head forwardly into said main cylinder, said extension from the plunger including a hollow portion passing through said head and into the power cylinder, a power piston on said extension in the power cylinder, and a differential piston on said extension in the differential cylinder, said head having means for attaching an air line, and also having a passage delivering air to said main cylinder behind its follower only when the air line is attached, said head also having passages for distributing air to the differential and power cylinders.
7. In apparatus of the class described, a main cylinder, a forward head thereon comprising a pump cylinder having an outlet, a plunger in said pump cylinder, an extension from said plunger reaching axially through said main cylinder, a follower in said main cylinder coaxial with the extension, said plunger being adapted to be drawn rearwardly of said pump cylinder, a head enclosing the rear of said main cylinder, a power cylinder extending coaxially rearward from said head, a differential cylinder extending coaxially from said head forwardly into said main cylinder, a power piston on said extension and located in the power cylinder, said extension from the plunger including a hollow portion passing through said head and into the power cylinder through the power piston, and a differential piston on said extension in the differential cylinder, said head

having means for attaching an air line and delivering air to said main cylinder behind its follower, said head also having a passage for distributing air to the interior of the differential cylinder and hence behind said power cylinder by way of said hollow portion of the extension, and valve means adapted to be set to exhaust air from said differential cylinder and consequently from said power cylinder to effect unbalance on the differential piston and a suction stroke of said plunger.

8. In apparatus of the class described, a main cylinder, pumping means at the front end of said cylinder, an operating extension from said pumping means passing through said cylinder, a follower surrounding said extension and positioned in said main cylinder, a coaxial power cylinder associated with said main cylinder, a piston in said power cylinder, said extension from the pumping means reaching to and having a hollow portion passing through said power piston, a differential piston attached to said extension, a cylinder therefor surrounding said hollow portion of the extension, said differential piston being exposed to pressure in the main cylinder, means for introducing priming air behind said follower in said main cylinder and means for introducing air under pressure to the differential cylinder, said hollow portion providing a communication between the differential cylinder and the power cylinder behind the power piston.

9. In apparatus of the class described, a lubricant supply compartment, a reciprocating pump adapted to withdraw and eject lubricant from said compartment, a follower in said compartment forming a lubricant chamber on the side nearest the pump and providing an air chamber on the other side, an extension movable with said pump, a differential member carried by said extension exposed to the pressure in the air chamber, the arrangement between the follower and said exposed differential member being such that normally the pump is driven by way of said extension to draw in a charge as said follower is driven to force the charge thereto, a power piston connected with the extension and differential member, and valve means for introducing air on the power side of said differential member, which side is opposite the side thereof exposed to the air chamber, and for introducing air to such side of the power piston as will force the pump to execute an ejecting stroke.

10. In apparatus of the class described, a lubricant supply compartment, a reciprocating pump adapted to withdraw and eject lubricant from said compartment, a follower in said compartment forming a lubricant chamber on the side nearest the pump and providing an air chamber on the other side, an extension movable with said pump, a differential member carried by said extension exposed to the pressure in the air chamber, the arrangement between the follower and said exposed differential member being such that normally the pump is driven by way of said extension to draw in a charge as said follower is driven to force the charge thereto, a power piston connected with the extension and differential member, and valve means for introducing air on the power side of said differential member, which side is opposite the side thereof exposed to the air chamber, and for introducing air to such side of the power piston as will force the pump to execute an ejecting stroke, said valve means being adapted also to exhaust air

from the differential member and power piston.

11. In apparatus of the class described, a lubricant supply compartment, a reciprocating pump adapted to withdraw and eject lubricant from said compartment forming a lubricant chamber on the side nearest the pump and providing an air chamber on the other side, an extension movable with said pump, a differential member carried by said extension exposed to the pressure in the air chamber, the arrangement between the follower and said exposed differential member being such that normally the pump is driven by way of said extension to draw in a charge as said follower is driven to force the charge thereto, a power piston connected with the extension and differential member, and valve means for introducing air on the power side of said differential member, which side is opposite the side thereof exposed to the air chamber, and for introducing air to such side of the power piston as will force the pump to execute an ejecting stroke, said valve means being adapted also to exhaust air from the differential member and power piston, the apparatus having a passage for the free flow of air to and from the space below the power piston, and a passage for exhausting the air from the differential member through the space under the power piston.

12. In apparatus of the class described, a lubricant supply compartment, a reciprocating pump adapted to withdraw and eject lubricant from said compartment forming a lubricant chamber on the side nearest the pump and providing an air chamber on the other side, an extension movable with said pump, a differential member carried by said extension exposed to the pressure in the air chamber, the arrangement between the follower and said exposed differential member being such that normally the pump is driven by way of said extension to draw in a charge as said follower is driven to force the charge thereto, a power piston connected with the extension and differential member, and valve means for introducing air on the power side of said differential member, which side is opposite the side thereof exposed to the air chamber, and for introducing air to such side of the power piston as will force the pump to execute an ejecting stroke, said valve means being adapted also to exhaust air from the differential member and power piston, the apparatus having a passage for the free flow of air to and from the space below the power piston, and said extension carrying a passage from the power side of the power piston to the power side of the differential member.

13. In a pump, a fluid reservoir, a reciprocating pump adapted to withdraw lubricant from the reservoir and eject it upon suction and compression strokes respectively, means for applying superatmospheric priming pressure inside of the reservoir and to the lubricant, differential means reciprocating with the pump normally exposed to said priming pressure and adapted to drive said pump through a suction stroke under said pressure, a power means reciprocating with said pump, and means for introducing air pressure on the power means in a direction to drive the pump through an ejecting stroke and at the same time to the differential means to at least partially counterbalance the effect of the priming air pressure thereon.
